JOHN B. TOTH, OF CHICAGO, ILLINOIS.

COMBINED PATTERN-DRAFTING DEVICE.

1,157,345.

Specification of Letters Patent.

Patented Oct. 19, 1915.

Application filed November 24, 1914. Serial No. 873,701.

To all whom it may concern:

Be it known that I, JOHN B. TOTH, a citizen of the United States of America, residing at Chicago, in the county of Cook and State of Illinois, have invented certain new and useful Improvements in Combined Pattern-Drafting Devices, of which the following is a specification, reference being had therein to the accompanying drawing.

This invention relates to a combined pattern-drafting device and has for its object to provide a device of such class, in a manner as hereinafter set forth, with means adapted to the formation of compound curves and of scroll-shaped curves as well as providing for the forming and cutting of patterns curvilinear in contour.

A further object of the invention is to provide in a manner as hereinafter set forth, a device of the class referred to, with means whereby the device can be adjusted to various sizes when the occasion so requires.

A further object is to provide a device of the class referred to which is simple in its construction and arrangement, strong, durable, efficient and convenient in its use, readily set up, and comparatively inexpensive to manufacture.

A further object of the invention is to provide a pattern-drafting device, in a manner as hereinafter set forth, which can be employed for drafting purposes, making of patterns, cutting of patterns from paper, thin metallic plate, lead, and which cannot only be operated manually, but with a machine if desired.

With the foregoing and other objects in view the invention consists of a novel construction, combination and arrangement of parts as hereinafter more specifically described and illustrated in the accompanying drawings, wherein is shown an embodiment of the invention, but it is to be understood that changes, variations and modifications can be resorted to which come within the scope of the claims hereinto appended.

In the drawings wherein like reference characters denote corresponding parts throughout the several views Figure 1 is an elevation of a device for scribing curves and drafting patterns and cutting patterns in accordance with this invention. Fig. 2 is a sectional elevation of one of the longitudinal bars of the frame, taken on line *a—a* Fig. 1. Fig. 3 is a plan of bar illustrated in Fig. 2.

Fig. 4 is a cross sectional view of Fig. 1, through the center thereof, taken on line *b—b*, Fig. 1. Figs. 5 to 14 are details. Fig. 15 is an elevation, broken away and Fig. 16 is a vertical sectional view of a strip capable of being flexed to provide a curve. Fig. 17 is a sectional view of a clamp.

Referring to the drawings in detail the device includes a frame including a side bar 1, having a longitudinal rib 2 on its upper face and which extends from a point removed from one end and terminates at the other end of said bar 1. The frame 1 further includes a pair of end bars 3, 4, and a side bar formed of two sections 5, 6. The end bar 3 has its upper face formed with a longitudinal rib 7 which extends from a point removed from one end of said bar and terminates at the other end thereof. The end bar 4 has its upper face provided with a longitudinal rib 8 which extends from a point removed from one end of the bar 4 and terminates at the other end thereof. The section 5 of a sectional side bar has its upper face formed with a longitudinal rib 9 which starts at a point removed from the inner end of said sections and terminates at the other end thereof. The section 6 of the sectional side bar has its upper face formed with a rib 10 which starts at the inner end of said sections 6 and terminates at a point removed from the outer end thereof. The ribs 2, 7, 8, 9, and 10 are disposed centrally with respect to their bars and each of said ribs is rectangular in transverse section. The ends of the bars of the frame overlap each other and are adjustably connected together by set screws 11. The inner ends of the sections 5, 6, overlap each other and are adjustably connected together by the set screw 12. Straddling the rib 2 is a holding member 13, which is maintained in position by a set screw 14. The holding member 13 has a pin 15, upon which is mounted the head 16, of a horizontal bar 17, which extends between the inner end of the sections 5, 6, as well as projecting therefrom.

Adjustably mounted upon the rib 2 is a plurality of curve retainers 18 and each of said retainers has its top formed with a groove 19, which flares from the center toward each end. The retainers straddle the rib 2 and are adjustably secured therewith through the medium of set screws 20. The retainers 18 carry binding screws 21 for a

purpose to be presently referred to. Straddling and shiftably mounted upon the rib 8 is a curve retainer 22, straddling and shiftably mounted upon the rib 7 is a curved retainer 23, straddling and shiftably mounted upon the rib 9 are curve retainers 24, 25, 26 and straddling and shiftably mounted upon the rib 6 are curve retainers 27, 28 and 29. Each of the retainers 22 and 29 is provided with a binding screw 30 and a set screw 20 and each of said curve retainers 22 and 29 has its top provided with a groove 32 which flares from the center toward each end. The binding screws 21 and 30 are capable of extending into the grooves of the curve retainers for a purpose to be presently referred to.

Mounted upon the rib 8 is a plurality of holding members constructed similar to the member 13, and mounted upon the pins 15 of the said holding members, upon the rib 8 are the heads 33, 34, of bars 35, 36. The bar 17 is provided with a holding member similar to the holding member 13, and the pin of the holding member carried by the bar 17, which is indicated at 36^a, has mounted thereon the head 37, of a bar 38^a, the latter extends longitudinally. The bar 35 extends at an inward inclination with respect to the bar 1 and is clamped to a bar 38 which is disposed at an opposite inclination with respect to the bar 35. The clamp between the bars 35, 38 is indicated at 39, being shown in (Fig. 11). The bar 38 has a head 70, and which is mounted upon the pin 15 of the holding member shiftably connected to the rib 7. The bar 38 is clamped to the bar 17 and the clamp is indicated at 40 (Fig. 14). The bar 38 is clamped to the bar 36 by a clamp 41, (Fig. 21). The various clamps are adjustably secured in position by set screws 42.

Adjustably mounted upon the bar 35, through the medium of the set screws 43, are curve retainers 44, 45, each of which has its upper face formed with a groove 46 flaring from the center toward each end and each of which is furthermore provided with a binding screw 47 which extends into the groove 46. The bar 38 is provided with curve retainers 48, 49, 50 and 51 and each of said retainers is adjustably connected to the bar 38 through the medium of the set screws 52. Each of the retainers 48 to 51 has a groove 53 in its top, which flares from its center toward each end and each retainer furthermore is provided with a binding screw 54 which extends in the groove. The bar 38^a is provided with a series of curve retainers 55 and each of which is adjustably connected to said bar with set screws 56 and each of which is provided with a groove in its top as at 57 which flares from the center toward each end. Each of the curve retainers has a binding screw 58 which extends into the groove 57. The bar 17 is provided with

curve retainers 59, each having a groove 60 in its upper face which flares from the center toward each end and said retainers 59 are maintained in said position by set screws 61. The clamp 39 is provided with a pocket 62, in which can be mounted, when desired, a curve retainer 63. The bar 35 is inset as at 64 and the bar 38 is inset as at 65 and extends below the bar 64. The bar 36 is also inset.

The arrangement of the bars and curve retainers is such that the curve retainers will be in alinement with each other. The curve retainers are employed for maintaining the flexible strip 66 in a curvilinear manner, as illustrated in Fig. 1. To change the curvature of the strip the retainers are shifted along the bars 35, 36, 38 and 38^a and upon the ribs 2, 7, 8, 9 and 10, and bar 17 and after moved to desired position are fixed in position through the medium of the adjusting screws.

In Figs. 15 and 16 of the drawings is illustrated a flexible strip 67, having a smooth top edge 72.

What I claim is:—

1. A device for the purpose set forth comprising a frame including side and end members provided with ribs, holding members shiftably mounted upon said ribs, bars connected to said holding members and further adjustably connected together, and curve retainers mounted upon said ribs and bars and capable of being shifted lengthwise of the ribs and bars.

2. A device for the purpose set forth comprising a frame including side and end members provided with ribs, holding members shiftably mounted upon said ribs, bars connected to said holding members, clamps for adjustably connecting said bars together, and curve retainers mounted upon said ribs and bars and capable of being shifted lengthwise of the ribs and bars, and means for maintaining said curve retainers in a position to which they have been shifted.

3. A device for the purpose set forth comprising a frame including side and end members provided with ribs, holding members shiftably mounted upon said ribs, bars connected to said holding members, clamps for adjustably connecting said bars together, and curve retainers mounted upon said ribs and bars and capable of being shifted lengthwise of the ribs and bars, and means for maintaining said curve retainers in a position to which they have been shifted, each of said curve retainers having one end thereof provided with a groove flaring from the center toward each end.

4. A device for the purpose set forth comprising a plurality of adjustable bars, means for supporting said bars, clamps for adjustably connecting certain of the said bars together, and curve retainers mounted upon

said supporting means and said bars and adjustable longitudinally of said means and said bars.

5 5. A device for the purpose set forth comprising a plurality of adjustable bars, means for supporting said bars, and curve retainers mounted upon said supporting members and said bars and adjustable longitudinally of said members and said bars, each of said 10 curve retainers having one end provided with a groove flaring from the center toward each end and adapted to receive a flexible strip whereby the walls of the groove will set in the strip in curvilinear form.

15 6. A device for the purpose set forth comprising a plurality of adjustable bars, means for supporting said bars, and curve retainers mounted upon said supporting members and said bars and adjustable longitudinally of 20 said members and said bars, each of said

curve retainers having one end provided with a groove flaring from the center toward each end and adapted to receive a flexible strip whereby the walls of the groove will set in the strip in curvilinear form, and 25 means for binding the strip in said grooves.

7. A device for the purpose set forth comprising a frame formed of a plurality of adjustable members, series of bars adjustably connected to said frame, clamps adjustably connecting said bars together and curve retainers mounted upon said members, bars, and clamps and capable of being shifted thereon.

30 In testimony whereof I affix my signature 35 in the presence of two witnesses.

JOHN B. TOTH.
